DESIGN FOR A SURFACE SUPPORTED LIGHTING FIXTURE

Clyde D. McCann, Des Moines, Iowa

Application March 25, 1935, Serial No. 56,033

Term of patent 7 years

To all whom it may concern:

Be it known that I, Clyde D. McCann, a citizen of the United States, residing in Des Moines, in the county of Polk and State of Iowa, have invented a new, original, and ornamental Design for a Surface Supported Lighting Fixture, of which the following is a specification, reference being had to the accompanying drawing, forming a part thereof.

Fig. 1 is a plan view, and Fig. 2 is an end view of a surface supported lighting fixture, showing my new design.

I claim:

The ornamental design for a surface supported lighting fixture substantially as shown.

CLYDE D. McCANN.
